[57] **CLAIM**

The ornamental design for a keyboard with integrated graphic tablet and wrist rests, as shown and described.

DESCRIPTION

FIG. 1 is a top front side perspective view of a keyboard with integrated graphic tablet and wrist rests.

FIG. 2 is a top plan view;

FIG. 3 is a front elevational view;

FIG. 4 is a rear elevational view;

FIG. 5 is a right side elevational view, the undisclosed left side elevational view is similar in appearance to the right side elevational view shown.

The undisclosed bottom view is flat and unornamented except for the inclusion of the supports.
